EX

OR D 14,235

Design No. 14,235, dated August 21, 1983.

UNITED STATES PATENT OFFICE.

K. LOCKWOOD FRENCH, OF NEW YORK, N. Y.

DESIGN FOR A PITCHER OR OTHER SIMILAR VESSEL.

SPECIFICATION forming part of Design No. 14,235, dated August 21, 1883.

Application filed January 29, 1883. Term of patent 14 years.

To all whom it may concern:

Be it known that I, K. LOCKWOOD FRENCH, a citizen of the United States, and a resident of the city, county, and State of New York, 5 have invented a new and original Design for a Pitcher or other Similar Vessel, of which the following is a specification.

My invention relates to the decorative arts. It relates especially to the designing of forms to vessels and their ornamentation.

My invention consists in forming the upper portion of a pitcher, vase, or similar vessel in the shape of the head of an elephant, while the trunk of the animal curves downward and 15 joins the body of the vessel in such a manner as to form a strong and convenient handle.

The accompanying photograph of a pitcher fully illustrates my invention. The body of the vessel is of the usual curved or vase-shaped 20 form, and the front portion of the top is given the usual shape for convenient pouring of the liquid. The other portion of the top is formed into the shape of the elephant's head, of such a size and aspect that the design is at once 25 clearly seen and understood by the beholder. The upper back edge of the vessel is the front or top of the head of the animal, while the ears are raised in such a manner as to form the 30 sides of the upper edge of the vessel for a considerable portion of the distance round the top, and join the spout near the front. This position of the head gives opportunity for the trunk to form in its natural and proper position the handle of the vessel. The lower end of the 35 trunk is turned upward a short distance after meeting the body of the vessel, thus preserving its natural position and giving beauty to the attachment. The mouth of the animal is represented open, the lower jaw resting against 40 the body of the vessel. The tusks are repre-

sented as severed close to the head. The body of the vessel is decorated in the usual manner to represent water.

It is evident that the precise form shown in the photograph need not be always adhered to. 45 Thus any form of vessel, whether of straight or curved sides, may be used in combination with my design. The mouth may or may not be represented as open. The ears of the animal may be formed in a different position. In 50 case the object of the design is a vase, the effigy will be formed on both sides and its size and the position of the ears may be somewhat modified.

My invention is obviously adapted to be carried out in combination with vessels made in all ordinary materials—metals, terra-cotta, and all kinds of earthenware—and for all purposes, either in designs for mere ornaments or in vessels for ordinary household use. 55

What I claim, and desire to secure by Letters Patent, is—

1. The combination, substantially as hereinbefore set forth, with the body of a pitcher, vase, or similar vessel, of the image or representation of the head and trunk of an elephant, which image or representation forms a part of said body and the handle thereto. 65

2. A pitcher, vase, or similar vessel in which the handle and upper portion of the body is 70 formed to represent the trunk and head of an elephant.

In testimony whereof I have hereunto subscribed my name this 27th day of January, A. D. 1883.

K. LOCKWOOD FRENCH.
